UNITED STATES PATENT OFFICE.

ROBERT HOFSTETTER, OF DOWNS GROVE, ILLINOIS, ASSIGNOR TO WESTERN ELECTRIC COMPANY, INCORPORATED, OF NEW YORK, N. Y., A CORPORATION OF NEW YORK.

METHOD OF AND APPARATUS FOR ASSEMBLING MEMBERS.

Application filed January 5, 1926. Serial No. 79,493.

This invention relates to a method of and apparatus for assembling members, and more particularly for assembling members of ceramic material.

5 This invention is particularly applicable in assembling protector blocks of the type used in open space cutouts, commonly employed in electrical circuits as a means for protecting against abnormal current surges. 10 These protector blocks, particularly of a type sometimes used in telephone circuits, may comprise an electrode of carbon or other suitable material fitted and cemented within a surrounding block 15 of non-conducting material such as porcelain or the like. The carbon electrode must be very accurately positioned within the block, one surface of the electrode being depressed below the surface of the block associated 20 therewith, within the limits of a few tenths of thousandths of an inch. This degree of depression represents the size of the open space air gap formed between the depressed surface of the carbon electrode and a second 25 electrode or block of conducting material bearing against the surface of the non-conducting block in service. Unless the size of the air gap is maintained within the above 30 mentioned limits, current surges within the circuit may either retard or prematurely cause an electrical discharge across the gap and obviously under such circumstances the assembled block and electrode would be 35 rendered ineffective as a circuit protecting device.

Objects of the present invention are to provide an improved method of and apparatus for accurately assembling ceramic members in an efficient and economical manner.

To attain these and other objects and in accordance with the general features of the invention, an apparatus is provided which includes a vertical magazine designed to receive a stack of protector blocks. The porcelain members of the blocks within the magazine have been previously assembled with carbon electrodes cemented therein, one surface of the assembly having been subjected to a lapping or grinding operation to render the surfaces of the porcelain block

member and electrode coplanar. The lowermost protector block in the magazine is fed into an elongated, electrically heated furnace through which the blocks are advanced 55 step by step at such a rate as to render the cement somewhat plastic by the time the block leaves the furnace. Each block upon emerging from the furnace is fed into a positioning mechanism wherein it is aligned with 60 the upper extremities of plunger members which subsequently engage the lower surface of the block and electrode so as to accurately establish the position of one with- 65 in the other. During this operation the 70 electrode is shifted or depressed until the upper surface thereof is a predetermined distance, which may be only a few thou- sandths of an inch below the surface of the block associated therewith. The bonding 75 cement is then quickly rehardened by a stream of air. The adjusted assembly is ejected and transferred to a suitable receiving tray. The cooperating parts of the 80 apparatus are driven from a main cam shaft, 75 a complete cycle of operation resulting from each revolution of the shaft.

These and other objects and features will be apparent from the following detailed description when considered in connection with 85 the accompanying drawings, in which—

Fig. 1 is a fragmentary side elevational view of an assembly apparatus disclosing an embodiment of the invention, with a portion of the sub frame broken away to disclose parts otherwise hidden;

Fig. 2 is a fragmentary end elevational view thereof shown partly in section;

Fig. 3 is a diagrammatic view of the operating cams and their respective roller followers showing the relative position of each cam surface with respect to the cam shaft;

Fig. 4 is a fragmentary vertical section taken on the line 4—4 of Fig. 2 with a protector block shown in dotted lines within 95 the positioning mechanism;

Fig. 5. is a horizontal detailed section taken on the line 5—5 of Fig. 2;

Fig. 6 is a detailed transverse vertical section of the positioning mechanism taken 100 on the line 6—6 of Fig. 5, the plunger members thereof being disclosed in operative

engagement with a positioned protector block;

Fig. 7 is a horizontal transverse section thereof taken on the line 7—7 of Fig. 6;

5 Fig. 8 is a perspective view showing in detail the lateral positioning mechanism and ejector bar;

10 Fig. 9 is an enlarged elevational view of an assembled protector block, representative 10 of the type adapted to be fed into the machine disclosed in Fig. 1;

Fig. 10 is a longitudinal vertical section of the protector block taken on the line 10—10 of Fig. 9;

15 Fig. 11 is a transverse vertical section of the block taken on the line 11—11 of Fig. 10, and

20 Fig. 12 is a similar sectional view, showing the protector block in association with a companion carbon electrode, the electrode within the block being disclosed in its final depressed position.

25 Referring to the drawings wherein like numerals designate similar parts throughout the disclosure the assembly apparatus includes a machine frame 15 suitably secured to a horizontal frame 16, the frame being formed with a bearing member 17 at one end and a similar bearing member 18 at the 30 other end thereof. A cam shaft 19 (Fig. 2) is disposed between and rotatably mounted in the bearing members 17 and 18, a spur gear 20 being keyed to the cam shaft 19 adjacent to the bearing member 18. Meshing 35 with the gear 20 is a smaller gear 21 which is formed integral with a clutch collar 22 rotatable upon a horizontal drive shaft 23. This drive shaft 23 may be mounted in bearing members (not shown) secured to the 40 frame plate 16 and driven from a suitable source of power (not shown). Clutch teeth 24 (Fig. 1) formed in the engaging surface of the clutch collar 22 are designed for engagement with companion teeth 25 formed 45 in a clutch member 26 secured to the shaft 23 and having an annular groove 27 formed therein. A hand wheel 30 secured to the outer extremity of a shaft 31 (Fig. 2) revolvable within a bearing formed on the 50 front surface of a sub frame 32, is adapted upon rotation to carry the clutch member 26 into and out of engagement with the clutch collar 22 through the medium of an eccentric head 33 provided at the inner extremity 55 of the shaft 31 and designed for actuation within the groove 27. A fixed shaft 34, parallel with the cam shaft 19 and the drive shaft 23, is journaled between bearing members 35 formed in the ends of the sub frame 60 32 (Fig. 4). Mounted upon the cam shaft 19 adjacent to the bearing member 17 (Fig. 4) is a feed cam 36, which is adapted upon rotation to actuate a protector block feeding mechanism 37 (Fig. 2) which will hereinafter be fully described.

Referring now to Figures 2 and 5 it will be observed that a frame block 38 bolted to the upper surface of the frame plate 16 supplies a mounting for the lower extremity of a vertical magazine 39. This magazine 39 70 is designed to receive a plurality of protector blocks 41 of the type shown (Figs. 9 to 12, inclusive). These protector blocks 41 are comprised of a channeled porcelain member 42 and a carbon electrode fitting in 75 an elongated opening therein and rigidly secured in position by a small portion of bonding cement 44 applied at each end thereof adjacent to the member 42 (Fig. 10). In this connection it is to be understood that 80 the upper surfaces of the electrode 43 and companion member 42 (Figs. 10 and 11) have been previously subjected to a grinding or lapping operation to render said surfaces 85 coplanar. The necessity of having these surfaces in coplanar relation will be readily understood as the description of the apparatus progresses. The blocks 41 are placed horizontally with their lapped surfaces uppermost within the magazine 39, the lowermost block being carried by gravity into a position to be advanced by the feeding mechanism 37 into a horizontal track 45 confined within an electric furnace 46.

90 The protector block feeding mechanism 37 (Figs. 2 and 5) includes an actuating finger 47 carried by a vertical fixture 48 suitably secured to the upturned portion of a horizontal slide rod 50 (Fig. 2). This rod 50 is reciprocably mounted within the frame block 38 and a guide block 51 mounted upon the frame plate 16. The inner end of the slide rod 50 engages a roller 52 carried at the upper extremity of a bell crank arm 53, the arm being angularly related to and 95 formed integral with a companion crank arm 54 which carries a roller 55 engaging the upper surface of the feed cam 36. A coil spring 56 interposed between the guide block 51 and a depending pin 57 secured at the outer extremity of the slide rod 50, serves to yieldingly maintain contact between the rod 50 and the roller 52 of the arm 53, and as a consequence thereof the roller 55 of the arm 54 is maintained in 100 operative engagement with the surface of the cam 36. From the true form of the feed cam 36 as disclosed in Fig. 3 it will be obvious that during each cycle of rotation, the roller 55 will experience a quick downward movement which will result in a relative advancing movement of the finger 47. The movement thus imparted to the finger 47 is sufficient to advance the lowermost block 41 105 within the magazine 39 into the furnace 46 and as the finger 47 is subsequently retracted it will clear the succeeding lowermost block within the magazine. Thus it will be understood that the next protector block advanced by the finger 47 will engage with the 110

115

120

125

130

first mentioned protector block and upon the successive reciprocation of the finger 47 a series of said blocks will be advanced through the furnace on the track 45. The 5 heat within the furnace 46 is regulated so that when the first mentioned block reaches the end of the furnace the cement 44 which forms a bond between the porcelain member 42 and the electrode 43, will be in a plastic 10 state. As the protector block emerges from within the furnace 46 it is advanced into a positioning mechanism 59 about to be described.

This positioning mechanism 59 is housed 15 within and supported by a frame housing 60 suitably secured to the upper surface of the frame plate 16 (Fig. 4). Piston members 61, 62, and 63 are vertically disposed within the housing 60, each piston being provided 20 at its lower end with an adjustable engaging nut 64, 65, and 66, respectively. These nuts cooperate with the free ends of hinged arms 68, 69, and 70, respectively. These arms 68, 69, and 70 are each provided with a roller 25 follower which engages with the respective surfaces of cams 71, 72, and 73, the opposite closed ends of the arms being hingedly mounted upon the shaft 34 (Fig. 2). It will be observed that the feeder cam 36 and the 30 cams 71, 72, and 73 are secured to spacing collars 74 which are keyed to the cam shaft 19. Contact between the engaging nut 64 and the arm 68 is maintained through the medium of a coil spring 75 (Fig. 4) interposed between a piston cap 76 and the lower surface of a block member 77 suitably secured to the upper portion of the frame 35 housing 60. A coil spring 80 positioned between the piston 62 and a stop screw 81 maintains the engagement of the nut 65 with the arm 69 and likewise a coil spring 82 between the piston 63 and a screw stop 83 maintains the contact of the nut 66 with the 40 arm 70.

Attention is now directed to certain co-operating parts of the positioning mechanism 59 located at the upper end thereof. From the description hereinbefore set forth in connection with the operating characteristics 45 of the furnace 46, it will be remembered that protector blocks are fed through said furnace and advanced to the positioning mechanism 59. As a protector block advances from within the furnace it is slid along the upper surface of the block member 77 and will assume the position shown by the dotted lines (Fig. 4). It will thus be brought to rest between the forward end of an ejector bar 84 and the inner surface 50 of a positioning finger 85. Referring to Figs. 4 and 8 it will be readily understood that this positioning finger 85 is formed at right angles to and at the forward extremity of a shank 86, which is longitudinally slidable within the ejector bar 84. When a

protector block 41 is carried along the surface of the block member 77 as hereinbefore described, the opening formed between the finger 85 and the end of the ejector bar 84 is sufficient in width to allow the protector block to be fed therebetween. Immediately subsequent to the advancement of the protector block, a vertical bar 87 (Figs. 1 and 8) which is mounted at its lower end in an arm 88 secured to and extending laterally 55 from the lower end of the piston 62, is actuated upwardly by the operation of the cam 72. The upper extremity of the vertical bar 87 is beveled and is adapted to engage with companion beveled surfaces provided 60 on the shank 86 and the ejector bar 84, the engagement resulting in the shank 86 and the finger 85 being actuated to the right (Fig. 4). This movement of the finger 85 is sufficient to cause a protector block positioned between the finger and the ejector bar 84 to be properly aligned with respect to the upper extremity of vertical plunger members 91 and 92. A spring 90 (Figs. 5 and 8) lodged within the advancing end of the 65 ejector bar 84 is designed to effect the immediate release of the positioned protector block from the finger 85 upon the downward movement of the vertical bar 87.

The plunger members 91 and 92 are vertically slidable within the piston 61 and are yieldingly maintained in their normal upwardly extending positions by means of springs 93 coiled about the lower ends of the plunger members and interposed between 70 the bottom of a chamber 94 formed in the upper portion of the piston 61 and shoulders 95 provided on the plunger members. The cap 76 suitably secured to the upper end of the piston 61 serves to limit the upward 75 movement of the plunger members 91 and 92 occasioned by the action of the springs 93. Immediately following the above mentioned aligning operation of the finger 85, the cam 71 functions to actuate the piston 61 upwardly, thereby bringing the upper ends of the plungers 91 into contact with the lower surface of the positioned porcelain member 42 and the plunger members 92 into contact with the lower surface of its companion 80 carbon electrode 43. The protector block 41 is thus carried upwardly into contact with the lower surface of a head 96 secured within a head block 97. This head block 97 is provided with an arm 98 formed at right 85 angles thereto, said arm being hingedly mounted on the outer side of the frame housing 60 adjacent to the upper surface of the frame plate 16. A conventional thumb screw 100 is adapted to retain the arm 98 in its normal vertical position as disclosed throughout the various figures. When it is desired to swing the head 96 and block 97 away from the frame housing 60, for the 90 purpose of cleaning and the like, it is only 95

necessary to turn the thumb screw 100, 90° and swing a locking hook 99 to the left (Fig. 1).

Referring to the head 96 as disclosed in Figs. 4, 6, and 7 it will be observed that the head is formed with a central elongated depending portion 101 which engages with the upper surface of the carbon electrode 43 when the plunger members 91 and 92 carry a positioned protector block 41 into engagement with the head as described. The depending portion 101 of the head 96 causes the carbon electrode 43 to be depressed within its companion porcelain member 42 a few thousandths of an inch, the bonding cement having been previously heated to a plastic state. While the plunger members 91 and 92 thus yieldingly hold the positioned protector block against the surface of the head 96, a cam 102 mounted upon the cam shaft 19 and adjacent to the spur gear 20 operatively engages with a roller follower carried at the free end of a hinged arm 103 (Fig. 2). A lug 104 formed on the arm 103 is thereby brought into engagement with an actuating button 105 of an air valve mechanism 106 connected with a source of compressed air supply (not shown) by means of a conduit 107. This valve mechanism is also connected, through the medium of a pipe line 108, with the lower end of the hinged arm 98. A passageway 110 extending throughout the length of the arm 98 communicates at its upper extremity with an annular passageway 111 formed within the head block 97 and surrounding the head 96. An opening 112 extending transversely of the head 96 serves to communicate the annular passageway 111 with a pair of apertures 113 vertically disposed within the head. From the foregoing it will be clear that when the lug 104 of the arm 103 engages the button 105 of the valve mechanism 106 a stream of air will be permitted to flow through the pipe line 108, thence into the passageway 110 of the hinged arm 98 to the annular passageway 111 and finally through the vertical apertures 113. A pair of vertical openings 114 within the head 96 (Figs. 6 and 7) oppositely disposed from the apertures 113 permit of the egress of air after it has been directed against the bonding cement 44 of the positioned protector block 41. The stream of air is directed to the block for a period of time which is sufficient to cause the hardening or setting of the cement. At the end of this period the cam 71 operates to lower the plunger members 91 and 92 and the cam 102 functions to cut off the air supply by actuating the valve mechanism 106. Immediately subsequent to the above mentioned functioning of the cams 71 and 102, a depression in the cam 73 permits the piston 63 to be actuated down-

wardly with the result that a lever arm 115 having a universal, ball connection with the piston 63 is quickly actuated to the left (Fig. 4). The upper end of the lever arm 115 is lodged within a recess formed on the underside of a bracket member 116 secured to the end of the ejector bar 84 by means of screws 117 and it will be obvious that the above mentioned actuation of the lever arm 115 will carry the ejector bar, which is 75 slidably mounted in guide bars 118, forwardly. The projector block lodged between the finger 85 and the forward end of the ejector bar will be moved along the upper surface of the block member 77 and finally delivered to a suitable receiving chute 119. During this ejection operation of the ejector bar 84, a fabric wiper 120 carried by said bar at the forward end thereof, serves to wipe the surface of the 80 depending portion 101 of the head 96 and thereby remove any foreign matter which may have been deposited thereon. Such foreign matter, if permitted to remain on the surface of the portion 101 might cause 85 the shifting of the carbon electrode 43 of the succeeding protector block within its companion porcelain member 42, to be in excess of the permissible limits of the required depression. The protector blocks 90 delivered to the chute 119 are in condition to be assembled with companion carbon electrodes 121, which as disclosed in Fig. 12, are adapted to bear against the surface 95 of the porcelain members 42 and an air gap 122 thus formed between the electrodes 121 and 43 will be within the dimensional requirements to effectively serve as a protecting means against current surges within 100 the circuit to which the assembly may be 105 applied.

In operation, protector blocks of the type disclosed are fed into the vertical magazine 39. Power supplied to the drive shaft 23 from a suitable source (not shown) results 110 in the rotation of the cam shaft 19 upon manipulation of the hand wheel 30 through the medium of the gears 20 and 21. The rotation of the feed cam 36 causes the oscillation of the bell crank arms 53 and 54 and the consequent horizontal reciprocation of the finger 47 of the feeding mechanism 37. By means of the successive reciprocations of the finger 47, protector blocks are fed 115 from the lower end of the magazine 39 and advanced into alignment within the electric furnace 46. The heat within the furnace renders the cement 44 of the advancing protector blocks plastic and as each block 120 emerges from said furnace it is fed into the positioning mechanism 59. The cam 72 then actuates the piston 62 and the vertical bar 87 carried thereby, with the result 125 that the finger 85 is actuated so as to effect the proper lateral alignment of the pro- 130

tector block now positioned between said finger and the ejector bar 84. Upon the downward movement of the vertical bar 87 the finger 85 is instantaneously released from the positioned protector block through the action of the confined spring 90 and the plunger members 91 and 92 are contemporaneously brought into engagement with the protector block through the action of the cam 71. The depending portion 101 of the head 96 causes the upper surface of the carbon electrode 43 within the positioned protector block to be shifted or depressed a few thousandths of an inch below the corresponding surface of its companion porcelain member 42. While the protector block is thus gripped between the head 96 and the plunger members 91 and 92 a stream of air is directed against said block, this stream of air being directed from the valve mechanism 106 which is controlled by means of the cam 102. After the cam 71 has permitted the lowering of the plunger members 91 and 92 and the cam 102 has caused the supply of air to be cut off, the cam 73 permits the lowering of the piston 63. The lowering of the piston 63 causes the lever arm 115 to actuate the ejector bar 84 and the positioned protector block is subsequently delivered to the receiving chute 119. Attention is invited to the diagrammatic views of the cams shown in Fig. 3 wherein the true form and relative positions of the cam surfaces are disclosed with the view of clearly disclosing the timing thereof.

Although the invention as herein illustrated and described is particularly well adapted for use in connection with apparatus for assembling protector block parts, it should be understood that the novel features thereof are capable of other applications and should be limited only by the scope of the appended claims.

What is claimed is:

1. A method of establishing accurate relationship between bonded members, which consists in rendering the bonding material of the members soft by means of heat, accurately shifting one member with respect to the other, and then applying a stream of gaseous medium directly to the heated bonding material.

2. A method of establishing accurate relationship between the bonded carbon electrode and insulating member of a protector block, which consists in feeding blocks in a continuous train through a heating chamber to soften the bonding material, applying a yielding force to an electrode and associated insulating member upon emergence from the chamber to accurately shift one with respect to the other, and then subjecting the associated bonding material to a stream of air while the electrode and insulating member are being held in shifted relation.

3. In an assembling apparatus for positioning bonded members, means for heating the bonding material of the members, a positioning mechanism designed to accurately shift members, and means for advancing the members from the heating means to the positioning mechanism.

4. In an assembling apparatus for positioning bonded members, means for heating the bonding material of the members, a positioning mechanism designed to accurately shift members, means for advancing heated members to the positioning mechanism, and means for subjecting the bonding material of the positioned members to a cooling medium to effect the quick setting thereof.

5. In an assembling apparatus for positioning bonded members, means for heating the bonding material of the members, a positioning mechanism adapted to engage opposed surfaces of each of the bonded members and accurately shift one with respect to the other, and means for advancing heated members to the positioning mechanism.

6. In an assembling apparatus for positioning associated block members, a positioning mechanism designed to accurately arrange the relative positions of the associated block members, a magazine for the block members, and means for advancing associated block members from the magazine to the positioning mechanism.

7. In an assembling apparatus for positioning bonded members, means for softening the bonding material of the members, a positioning mechanism designed to accurately shift one member with respect to the other, and means for advancing bonded members from the softening means to the positioning mechanism.

8. In an assembling apparatus for positioning bonded members, heating means for rendering the bonding material of the members soft, a positioning mechanism designed to accurately shift one member with respect to the other, means for advancing members from the heating means to the positioning mechanism, and means for causing the bonding material to set quickly after the positioning operation.

9. In an assembling apparatus for positioning bonded members, means for softening the bonding material of the members, a fixed positioning member, yielding positioning plunger members, said positioning members adapted to cooperate in accurately establishing relative positions of the bonded members, mechanism for receiving and accurately locating bonded members in position to be acted upon by the positioning members, and means for advancing bonded members from the softening means to the locating mechanism.

10. In an assembling apparatus for posi-

tioning bonded members, a heating chamber for softening the bonding material of the members, a positioning mechanism adapted to accurately establish relative positions of bonded members, a container for the members, and a reciprocating mechanism designed to intermittently feed members from the container into the heating chamber and advance said members in a step by step manner through the heating chamber to the positioning mechanism.

11. In an assembling apparatus for positioning bonded members, a heating means for softening the bonding material of the members, a positioning mechanism designed

to accurately establish relative positions of bonded members, means for advancing members to the heating means and positioning mechanism, means for applying a stream of air to the softened bonding material, and a mechanism comprising a plurality of timed cams driven from a common source, designed to actuate the feeding means, positioning mechanism, and air applying means.

In witness whereof, I hereunto subscribe my name this 22 day of December, A. D. 1925.

ROBERT HOFSTETTER.
